(57) **CLAIM**

The ornamental design for a computer display screen with graphical user interface for navigation, as shown and described.

DESCRIPTION

FIG. 1 is a front view of a computer display screen with graphical user interface for navigation in accordance with a first embodiment;

FIG. 2 is a front view of a second embodiment thereof; and, FIG. 3 is a front view of a third embodiment thereof.

The heavy-weight dotted line segment connecting pin icons is included in the claimed design.

The longer-incremented broken-line rectangle illustrates a computer display screen and forms no part of the claimed design. The shorter-incremented broken lines outside the rectangle illustrate an electronic device and form no part of the claimed design. The shorter-incremented broken lines within the rectangle illustrate portions of a graphical user interface and form no part of the claimed design.
